(57) **CLAIM**

The ornamental design for a barrier or wall mounting apparatus, as shown and described.

DESCRIPTION

FIG. 1 is an isometric view of the barrier or wall mounting apparatus showing my new design;

FIG. 2 is a reduced scale front elevational view of FIG. 1, with the backside elevational view being the mirror image of the front.

FIG. 3 is a left side elevational view of FIG. 2.

FIG. 4 is a right side elevational view of FIG. 2; and,

FIG. 5 is the top view of FIG. 2.

The broken line showing of a sign mount, sign and barrier are for illustrative purposes only and form no part of the claimed design.
